Primary Examiner — Austin Murphy(74) *Attorney, Agent, or Firm* — Michael Best & Friedrich LLP(57) **CLAIM**

I claim the ornamental design for a jigsaw, as shown and described.

DESCRIPTION

FIG. 1 is a front perspective view of a jigsaw in accordance with an embodiment of the present invention.

FIG. 2 is a left side view of the jigsaw of FIG. 1.

FIG. 3 is a right side view of the jigsaw of FIG. 1.

FIG. 4 is a front view of the jigsaw of FIG. 1.

FIG. 5 is a rear view of the jigsaw of FIG. 1.

FIG. 6 is a top view of the jigsaw of FIG. 1; and,

FIG. 7 is a bottom view of the jigsaw of FIG. 1.

The portions of the jigsaw shown in broken lines are included for the purpose of illustrating environment and form no part of the claimed design.

1 Claim, 7 Drawing Sheets# US D887,806 S
